UNITED STATES PATENT OFFICE.

HARRIS D. DUNTON, OF SCHENECTADY, NEW YORK, ASSIGNOR TO GENERAL ELECTRIC COMPANY, A CORPORATION OF NEW YORK.

ELECTRIC SWITCH.

Application filed May 28, 1926. Serial No. 112,401.

My invention relates to improvements in electric switches, such as circuit breakers for interrupting electric circuits on the occurrence of abnormal circuit conditions, and has 5 for an object to provide an improved circuit breaker which can not be maintained in the circuit closed position during the existence of predetermined conditions.

My invention will be better understood 10 from the following description taken in connection with the accompanying drawings, and its scope will be pointed out in the appended claims.

In the accompanying drawings, Fig. 1 is 15 a side elevation of a circuit breaker embodying my invention and shown in the circuit closed position, Figs. 2 and 3 are similar to Fig. 1 except that the circuit breaker is shown in the partly open and fully open positions, respectively, and Fig. 4 illustrates in perspective a part of the circuit breaker mechanism.

Referring now in particular to Figs. 1, 2, and 3, I have shown my invention embodied 25 in an electric switch which, for the purpose of illustration, is shown as a single pole carbon break circuit breaker, but my invention is not limited to a single pole circuit breaker or to a circuit breaker of the type having 30 relatively movable cooperating contacts separable in air. In these figures, the circuit breaker is shown mounted on a suitable supporting structure such as a base or panel 10 of insulating material. The circuit breaker 35 comprises relatively movable cooperating contacts including stationary contacts 11 and 12 having studs 13 and a movable contact or electric current conducting member such as a resilient brush 14 cooperating with the 40 contacts 11 and 12 to control a circuit through the circuit breaker. The circuit breaker may be provided with cooperating secondary and tertiary contacts 15 and 16 respectively, to take the arc when the circuit breaker is 45 opened.

For moving the brush 14 to the circuit closed position, the circuit breaker is provided with a trip-free operating mechanism embodying my invention. In the illustrated 50 type of circuit breaker to which my invention is particularly applicable, this mechanism comprises an operating member such as a handle lever 17, mounted on a floating center such as the pivot 18 which is movably

supported as by the free ends of links 19, 55 the other ends of which are mounted on a stationary pivot 20. The movable circuit controlling member or brush 14 is suitably secured to a brush carrying member or switch arm 21 which is mounted on a stationary pivot 22 and biased by the strain on the brush and gravity to the circuit open position.

In order to tie the switch arm 21 to the operating lever 17 for movement thereby to 65 the circuit closed position so that a rigid connection cannot be maintained between them when the switch is operated during the existence of abnormal conditions, I provide, 70 in accordance with my invention, between these members a variable length connection such as the link 23, the effective length of which is subject to change under the bias of the arm 21. The link 23 is slotted and connected through the slot 24 to one of the 75 members of the circuit breaker mechanism, such as the lever 17, by the pivot 18, and is suitably connected to another member of the mechanism, such as the arm 21, as by a pivot 25. In order to have a change in the effective length of the link 23, that is, the distance 80 between the pivots 18 and 25, the slot 24 is so formed that the path of movement relatively to the link of the center of the pivot 18 as, the link moves from one position to 85 another on the pivot 18, has a variable radius of curvature, which is a maximum when the pivot 18 is in the upper end of the slot 24 as in Figs. 1 and 3, and a minimum when the pivot 18 is in the lower end of the slot as in 90 Fig. 2. The slot 24 may be kidney-shaped, as shown, with a hump or inwardly extending portion 26, the purpose of which will hereinafter be explained.

With this arrangement, it is obvious that 95 the link 23 is constructed and arranged for both rotatory and translatory movement relatively to the operating lever 17. In order to prevent such movement when the link 23 is in a position relatively to the lever 17 such 100 that the effective length of the link is a maximum, as when the pivot 18 is in the upper portion or end of the slot 24, I provide a latching means for holding the link 23 and the lever 17 against relative movement so 105 that the link 23 becomes in effect a rigid arm or extension of the lever 17. The latching means may be of any suitable type, and, as

shown, is of the so-called "shock-proof" type, such as disclosed in United States Letters Patent 1,589,924 to Winfield A. Atwood, issued June 22, 1926, and assigned to the same assignee as this invention. As shown, the latching means is mounted on the operating lever 17 and comprises a main latch 27 arranged to engage a shoulder 28 on the link 23, an auxiliary latch 29 arranged to engage the tail portion 30 of the main latch, and a spring 31 for biasing the latches to the latching position. The spring 31 is so connected to the latches 27 and 29 relatively to the respective pivots 32 and 33 thereof as to exert on the latches torques substantially directly proportional to their masses.

For releasing the latching means, and thereby effecting the opening of the circuit breaker, a trip lever, which, as shown, is mounted on a pivot 34 in the switch arm 21, has an arm 35 which, on movement of the trip lever in one direction, clockwise as shown in the drawings, moves the latch 29 out of engagement with the tail portion 30 of the latch 27. This latch 27 is so constructed and arranged as to cause it to slide off the lug 28 of the link 23 when released by the latch 29. This is accomplished by having the angle whose vertex is the latching point and which is determined by the latching point and the pivots 25 and 32 obtuse. The trip lever may be actuated to release the latch 29, either manually, as by pushing on a knob 36, secured to an arm of the trip lever, or automatically by an electroresponsive device. This device may be operative in response to abnormal conditions on the circuit controlled by the circuit breaker. Such a device is herein illustrated as comprising a magnetic frame or yoke 37 operatively related to one terminal or contact 11 of the circuit breaker, as is well known to the art, and a cooperating armature 38 which is arranged when attracted to the frame 37 as on the occurrence of excess currents to engage an arm 39 on the trip lever and thereby effect the release of the latches 27 and 29. The weight of the trip lever is so distributed as normally to tend to turn it counter clockwise against a stop 40 on the switch arm 21. The electroresponsive device is provided with means for varying its range of operation. This means, as illustrated, comprises a calibrating screw 41 which supports the free end of the armature 38 and is adjustable to control the initial position thereof.

While the electroresponsive device shown is of the type responsive to predetermined current conditions, it is to be understood that my invention is not limited to this means for actuating a tripping member arranged to release the latch 29, the means shown being merely illustrative of one device I may use. Obviously, I may use any means,

either automatic in action and operative in response to some predetermined condition, or manually operated, the only requisite being that the means be adapted to be operated to release the latch 29.

The links 19 and the link 23 form a toggle which, in the closed position of the circuit breaker, as shown in Fig. 1, is underset, that is, the pivot 25 does not cross the line through the centers of the pivots 18 and 20 when the arm 21 is moved to the circuit closed position. The switch arm 21 and the link 23 also form a toggle which, on clockwise movement of the lever 17, is arranged to be overset, that is to say, the pivot 25 crosses the line through the centers of the pivots 18 and 22. The amount of overset of the toggle 21-23 is limited by the toggle 19-23 which is restrained to hold the brush 14 in circuit closing position by any suitable means such as a catch 42 mounted on a pivot 43 in the operating lever and arranged to slide over and engage a projection such as a pin 44 on the arm 21. The length of the toggle 21-23 may be considered as the sum of the distances between the center of the pivot 25 and the centers of the pivots 18 and 22 respectively. This toggle length varies in accordance with the effective length of the link 23 and is greater than the distance between the pivots 18 and 22 when the pivot 18 is in the upper portion of the slot 24. In the closed position of the circuit breaker, the biasing force due to the brush pressure and also to gravity exerts on the link 23 a force which acts through the pivot 25 and tends to rotate the link 23 on the pivot 25, but the rotation is prevented by the latches 27 and 29 while in the latching position.

When the latch 29 is released as by clockwise movement of the trip lever, the link 23 would be free to rotate on the pivot 25 if this pivot were not constrained to move in the arc of a circle whose radius is the distance between the pivots 22 and 25. Consequently, the link 23 under the forces acting thereon, tends to rotate about the pivot 25 and thereby to increase the distance between the pivots 18 and 22. Since the pivot 18 can not move relatively to the pivot 22 to increase this distance while the latch 42 engages the pin 44, the link 23 is translated or moved bodily on the pivot 18 to the final position shown in Fig. 2. This movement decreases the distance between the pivots 18 and 25 and consequently the sum of the distances between the pivot 25 and the pivots 18 and 22 respectively to a value equal to or less than the distance between the pivots 18 and 22. The toggle center or pivot 25 of the overset toggle 21-23 can therefore cross back over the line joining the pivots 18 and 22 to the underset position shown in Fig. 2 where the circuit breaker is partly

open. In this position, the spring 31 maintains the latch 29 against the arm 35 of the tripping lever which is against the stop 40, and the latch 27 against a lug on the latch 5 29.

In order to reset the link 23 to its initial position or position of maximum effective length after the collapse of the toggle 21—23, I provide suitable means such as a 10 lug 45 on the link 23 arranged in the path of movement of a cooperating lug 46 on the brush arm 21 so as automatically to engage and push the link 23 into its initial position during the final part of the opening movement of the circuit breaker. Fig. 2 shows the lug 46 about to engage the lug 45 after the toggle 21—23 has collapsed, and Fig. 3 shows the lugs in engagement and the link 23 restored to its initial position. When 20 the link 23 is pushed back into its initial position, the edge 47 of the link abuts the upper end of the latch 27, thereby turning it clockwise from the position shown in Fig. 2 to the position shown in Fig. 3, and 25 further stressing the spring 31.

In order to close the circuit breaker, the link 23 must first be latched to the operating lever 17. To do this, the operating lever is moved counter clockwise from the full line 30 position shown in Fig. 3 to the dot and dash line position. Counter clockwise movement of the catch 42 about its pivot 43 is limited by a stop 48 on the operating lever so that the catch 42 rides clear of the pin 44 as the 35 lever is moved to latching position. In this movement of the lever 17, the latch 27 slides along the edge 47 of the link 23 under the bias of the spring 31 until it passes on to the lug 28. The latch 29, also under the 40 bias of spring 31 and clear of the trip lever arm 35, engages the tail 30 of the latch 27, as shown by the dot and dash lines. The link 23 is now in effect a rigid arm of the operating lever, which, when moved clockwise, oversets the toggle 21—23 and moves the switch arm 21 into the circuit closing 45 position. During the clockwise movement of the lever 17 to close the circuit breaker, there is a tendency for the link 23 to move bodily on the pivot 18 away from its latch 27. This tendency occurs after the pivot 25 crosses the line of the pivots 18 and 22 in the oversetting movement of the toggle 21—23. Any movement resulting from this 50 tendency is prevented by the inwardly extending portion 26 of the link, the size and shape of this portion being dependent on the relative proportioning and positioning of the various cooperating parts. In the 55 closing movement of the lever 17, a lug 49 thereon abuts the arm 21 and prevents any possibility of oversetting the toggle 19—23. When the operator stops pulling or pushing down on the operating lever 17, the bias of 60 the parts takes up all lost motion so that 65

the lug 49 does not abut the arm 21, as shown in Fig. 1. Obviously, if any attempt is made to close the circuit breaker while abnormal line conditions prevail, the trip lever will be actuated as soon as the circuit 70 is completed through the circuit breaker. Consequently, the link 23 will be released and the brush 24 will take the circuit open position, even though the operator still holds down on the handle lever 17. The circuit 75 breaker, therefore, cannot be maintained closed during the existence of predetermined conditions, such as an abnormal circuit condition, or in other words, is trip-free from 80 the handle.

While I have shown and described only one embodiment of my invention, I do not desire to be limited to the exact arrangement shown and described, but seek to cover in the appended claims all those modifications that fall within the true spirit and scope of my invention.

What I claim as new and desire to secure by Letters Patent of the United States, 90 is:—

1. A movable switch member, an operating member, and a link connecting the members, said link being slotted and pivoted through the slot to one of the members, the slot being so shaped that the path of movement of the link pivot relatively to the link has a variable radius of curvature whereby to permit a change in the distance between the connections of the link to the respective members. 95

2. A movable switch member, an operating member, a link connecting the members, said link being slotted and pivoted through the slot to one of the members, the slot being so shaped that the path of movement of the link pivot relatively to the link has a variable radius of curvature whereby to permit a change in the distance between the connections of the link to the respective members, and latching means for holding one of said members and said link against 105 relative movement.

3. A pivoted switch arm, a pivoted operating lever therefor, and a link pivoted to the arm, said link being slotted and pivoted through the slot for movement on the pivot of the operating lever, the path of movement of the pivot relatively to the link having a variable radius of curvature whereby to permit a change in the distance between the 110 link pivots.

4. A pivoted switch arm, a pivoted operating lever therefor, a link pivoted to the arm, said link being slotted and pivoted through the slot for movement on the pivot of the operating lever, the path of movement of the pivot relatively to the link having a variable radius of curvature, whereby to permit a change in the distance between the link pivots, and latching means arranged 115 120 125 130

when the link is positioned with the operating lever pivot in one end of the slot to hold the lever and the link against relative movement.

5. A pivoted switch arm biased for movement to one position, a pivoted operating lever for moving the arm to another position, a link pivoted to the arm and forming therewith a toggle arranged to be restrained 10 to hold the arm in the other position, said link being constructed and arranged for rotatory and transulatory movement relatively to the operating lever and provided with latching means for preventing such movement whereby under the bias of the arm when in the other position a change in the 15 length of the toggle is produced to allow the movement of the arm to the one position upon the release of the latching means.

20. 6. A pivoted circuit controlling member biased for movement to the circuit open position, an operating lever for moving the member to the circuit closed position, a link connecting the member and the lever, said link 25 being constructed and arranged for rotatory and transulatory movement on the pivot of the lever and being subjected to the bias of the member, latching means arranged on movement of the lever in one direction to 30 engage the link in one position and to hold it and the lever against relative movement, said link and member forming a toggle whose length in the latched position of the link is greater than the distance between 35 the pivots of the member and the lever whereby on movement of the operating member in the opposite direction the member is moved to the circuit closed position.

7. A pivoted switch member biased for 40 movement to one position, a pivoted operating member for moving the switch member to another position, a variable length connection between said members comprising a slotted link pivoted through the slot to one 45 of the members, the slot being constructed and arranged to provide a path of movement for the link pivot relatively to the link having a variable radius of curvature whereby to change the length of the connection 50 and latching means for holding the link in a position to maintain the maximum length of the connection against the bias of the switch member, said link and said switch member forming a toggle arranged to be 55 overset on movement of the operating member in a direction to move the switch member to the other position.

8. A pivoted switch member biased for 60 movement to one position, a pivoted operating member for moving the switch member to another position, a variable length connection between said members comprising a slotted link pivoted through the slot to one 65 of the members, the slot being constructed and arranged to provide a path of movement

for the link pivot relatively to the link having a variable radius of curvature whereby to change the length of the connection, latching means for holding the link in a position to maintain the maximum length of the 70 connection against the bias of the switch member, said link and said switch member forming a toggle arranged to be overset and restrained on movement of the operating member in a direction to move the switch 75 member to the other position, and means for releasing the latching means whereby under the bias of the switch member the link is moved to a position to shorten the length 80 of the connection between the members and thereby permit the toggle to collapse.

9. A trip-free circuit breaker mechanism comprising a switch member biased for movement to one position, an operating member mounted for movement on a floating 85 center, and a connection between said members constructed and arranged to have its effective length changed under the bias of said switch member.

10. A trip-free circuit breaker mechanism 90 comprising a switch member biased for movement to one position, an operating member for moving the switch member to another position mounted for movement on a floating center, and a link for connecting 95 said members constructed and arranged for both rotatory and transulatory movement relatively to one of the members whereby the effective length of the connection is variable under the bias of the switch member. 100

11. A trip-free circuit breaker mechanism comprising a switch member biased for movement to one position, an operating member for moving the switch member to 105 another position mounted for movement on a floating center, a link for connecting said members constructed and arranged for both rotatory and transulatory movement relatively to one of the members whereby the effective length of the connection is variable under the bias of the switch member, and latching means for preventing such relative movement whereby the operating member 110 can be actuated in a direction to move the switch member to the other position. 115

12. A trip-free circuit breaker mechanism comprising a switch member biased for movement to one position, an operating member for moving the switch member to another position mounted for movement on a floating center, a link for connecting said members constructed and arranged for both rotatory and transulatory movement relatively to one of the members whereby the effective length of the connection is variable under the bias of the switch member, latching means for preventing such relative movement whereby the operating member can be 120 actuated in a direction to move the switch 125 member to the other position. 130

member to the other position, and means for releasing the latching means whereby to permit such relative movement.

13. A trip-free circuit breaker mechanism comprising a switch arm biased for movement to the circuit open position, an operating lever for moving the arm to the circuit closed position against the bias thereof mounted on a floating pivot, a link connecting said arm and lever and arranged for both rotatory and translatory movement relatively to the lever under the bias of the arm, latching means for preventing such relative movement arranged to hold the link in an initial position whereby the lever can be actuated to move the arm to the circuit closed position, means for effecting movement of the link from its initial position under the bias of the arm arranged to release the latching means whereby to permit movement of the arm to the circuit open position, and means controlled by the arm and arranged during the opening movement thereof to restore the link to its initial position.

25. 14. A trip-free circuit breaker mechanism comprising a switch member biased for movement to one position, an operating member for moving the switch member to another position mounted for movement on a floating center, a connection between said members constructed and arranged for both rotatory and translatory movement relatively to one of the members under the bias of the switch member, latching means for preventing such relative movement arranged to hold said connection in an initial position whereby the operating member can be actuated in a direction to move the switch member to the other position, means for releasing said latching means whereby to effect movement of the connection from its initial position under the bias of the switch member and means arranged to restore the connection to its initial position during the movement of the switch member to the one position.

15. A pivoted circuit controlling member biased for movement to the circuit open position, an operating lever for moving the member to the circuit closed position, a link connecting the member and the lever, said link being constructed and arranged for rotatory and translatory movement on the pivot of the lever and being subjected to the bias of the member, latching means arranged on movement of the lever in one direction to engage the link in one position and to hold it and the lever against relative movement, said link and member forming a toggle whereby on movement of the operating lever in the opposite direction, the member is moved to the circuit closed position, means for holding the member in the circuit closed position while the latching means is in latching position, and means for releasing

the latching means whereby to effect, under the bias of the member, movement of the link to another position relatively to the lever such that the length of the toggle is changed.

16. A pivoted switch member biased for movement to one position, a pivoted operating member for moving the switch member to another position, a link constructed and arranged for rotatory and translatory movement on the pivot of one of the members, said link being connected to the other member and subjected to the bias of the switch member, latching means arranged on movement of the operating member in one direction to engage the link and hold it in one position relatively to the one member, said link and the other of said members forming a toggle whereby on movement of the operating member in the opposite direction the switch member is moved to the other position, means for holding the switch member in the other position while the latching means is in the latching position, and means for releasing the latching means whereby to effect the movement of the link to another position relatively to the one member such that the length of the toggle is changed.

17. A pivoted switch member biased for movement to one position, a pivoted operating member for moving the switch member to another position, a link constructed and arranged for rotatory and translatory movement on the pivot of one of the members, said link being connected to the other member and subjected to the bias of the switch member, latching means arranged on movement of the operating member in one direction to engage the link and hold it in one position relatively to the one member, said link and the other of said members forming a toggle whereby on movement of the operating member in the opposite direction the switch member is moved to the other position, means for holding the switch member in the other position while the latching means is in the latching position, and means for releasing the latching means whereby to effect the movement of the link to another position relatively to the one member such that the length of the toggle is decreased and means for resetting the link in its first position during the movement of the switch member to the other position.

18. A pivoted circuit controlling member biased for movement to the circuit open position, an operating lever for moving the member to the circuit closed position, a link connecting the member and the lever, said link being constructed and arranged for rotatory and translatory movement on the pivot of the lever and being subjected to the bias of the member, latching means arranged on movement of the lever in one direction to engage the link in one position and to hold it and the lever against relative movement.

movement, said link and member forming a toggle whereby on movement of the operating lever in the opposite direction, the member is moved to the circuit closed position, means for holding the member in the circuit closed position while the latching means is in latching position, means for releasing the latching means whereby to effect, under the bias of the member, move-

ment of the link to another position relatively to the lever such that the length of the toggle is decreased, and means mounted on the member and arranged to reset the link in its first position during the movement of the member to the circuit open position. ¹⁰

In witness whereof, I have hereto set my hand this 27th day of May, 1926.

HARRIS D. DUNTON. ¹⁵
